UNITED STATES PATENT OFFICE.

ISIDOR DINSTMAN, OF NEW YORK, N. Y., ASSIGNOR TO DIEL WATCH CASE CO., INC.,
A CORPORATION OF NEW YORK.

DESIGN FOR A COMBINED WRIST WATCHCASE, STRAP, AND BUCKLE.

Application filed August 4, 1927. Serial No. 22,996. Term of patent 14 years.

To all whom it may concern:

Be it known that I, ISIDOR DINSTMAN, a citizen of the United States, residing at New York city, county of the Bronx, and State of New York, have invented a new, original, and ornamental Design for Combined Wrist Watchcase, Strap, and Buckle, of which the following is a specification, reference being had to the accompanying drawing, forming a part thereof.

Fig. 1 is a plan view of a combined wrist watchcase, strap and buckle, showing my new design. Fig. 2 is an edge view.

I claim:

The ornamental design for a combined wrist watchcase, strap and buckle as shown.

ISIDOR DINSTMAN.
